UNITED STATES PATENT OFFICE.

CHARLES J. MOSES, OF BOGOTA, NEW JERSEY.

TORPEDO-GUARD FOR SHIPS.

1,317,094.

Specification of Letters Patent. Patented Sept. 23, 1919.

Application filed January 11, 1918. Serial No. 211,424.

To all whom it may concern:

Be it known that I, CHARLES J. MOSES, a citizen of the United States, residing at Bogota, in the county of Bergen and State 5 of New Jersey, have invented new and useful Improvements in Torpedo-Guards for Ships, of which the following is a specification.

The object of the invention is to provide 10 a comparatively simple, relatively inexpensive and efficient means for protecting a ship or other water craft from the damaging effects of torpedoes approaching the same either from the side or rear, such means 15 being adapted to be arranged in operative position when required, and to be removed or folded or stored when its use is unnecessary, to avoid the inconvenience incident to those protective means which are permanently located and serve to a greater or less 20 extent to impede the progress of the vessel.

Further objects and advantages will appear hereinafter, and while the essential features of the preferred embodiment of the 25 invention are disclosed, it will be understood that the same may be modified as required, within the scope of the appended claims, to adapt the same to craft designed for different purposes and services without 30 parting from the principles involved.

In the drawings:

Figure 1 is a view in side elevation of a steamship with the improved guard attached thereto.

Fig. 2 is a top plan view of the structure of Fig. 1. Fig. 3 is a detailed cross sectional view through the guard members and the attendant side of the ship.

Fig. 4 is a detailed plan view of a section 40 of one of the guard members, the guide therefor being shown in section.

Fig. 5 is a detailed sectional view showing a section of one of the guard members and the clip by which it is carried in the 45 slide.

The apparatus involves essentially a buoyant guard member 10 which is adapted when in operative position to float on the surface of the water, partly submerged, and obviously to a depth sufficient to constitute an effective deflector to divert a torpedo encountering the same, so as to cause such torpedo to pass either under or to the side of the vessel, said guard being maintained 55 at such a distance from the hull of the vessel as to insure the safety of the latter in

the event that the torpedo should explode on impact with the guard; together with supporting guiding means whereby said guard proper may be moved to and from its operative position, and means whereby a substitution of guards may be effected, so that in the event of injury to or destruction of one guard it may promptly be replaced by another designed and adapted to perform 65 the designed function.

Obviously the floating guard member may be variously constructed to serve the purpose indicated, but in the form illustrated in the drawing, it consists of a substantially 70 cylindrical shell of compartmental construction, the upper compartment 11 being airtight and constituting a float, while the lower compartment 12, which is normally empty, is provided with water inlet openings 13 whereby when the device comes in contact with the water, the latter flows into this water compartment and permits the sinking of the guard to the desired 75 depth where it is normally sustained by the air compartment. To facilitate the filling of the water compartment air exhaust tubes 14 may be employed.

These guards are arranged one on either 80 side of the ship, either for joint or independent use, and preferably, especially in connection with vessels of any particular size, they may be made in sections as illustrated, to facilitate the movement thereof toward and from their operative positions. 85 Also, in order to offer minimum obstacles to the progress of the vessel, they should be reduced at the forward end as indicated at 15. These guards are preferably provided with shackle rings 16, or the equivalent 90 thereof, whereby tackle may be attached, to lift the guards when not required.

Moreover said guards, or the sections thereof, are preferably mounted to slide upon guide members 17 which are shown as 100 being grooved at 18 to provide means for effective engagement of clips 19 on the guard, said slots being open at their lower ends so that in the event of injury to a guard or guard section, sufficient to destroy 105 the efficiency of the float element thereof, said guard or section will sink and drop from the guides, and in order to provide for this contingency, a second set of guards 20 may be arranged upon the guides in position to at once take the place of the damaged guard or guard section.

These guides may be supported at the desired distance from the hull of the craft as by means of bars 21 or the equivalent thereof, preferably having a hinged or pivotal connection at opposite ends respectively with the hull of the vessel and said guides, the joints being of any suitable practical construction which may adapt them, for example, to be folded within the contour of the hull, when not in use, so as to maintain the general exterior appearance of the latter. Also these supporting bars may be suitably braced as shown at 22 to resist forward and rearward strains and prevent displacement of the guard relatively to the hull of the craft, especially during the progress of the latter.

As with the side guards, the rear or stern guard which corresponds in general construction with that described, may be mounted in any suitable manner, adapting it to be withdrawn from the water and folded or stored when not required. For example, the guide members 23 may be supported by bars 24, and may be mounted to have both a sliding and pivotal relation therewith, so that the guards may be drawn toward the hull and thus elevated to remove the same from the water, or the bars 30 may be swung upwardly and secured in any preferred manner.

What is claimed is:—

1. A torpedo guard for water craft comprising a plurality of guide members having means for supporting themselves at a

distance from the hull of the craft, and a plurality of superposed buoyant guard members having means by which they are slidably carried on the guide members, each guard member having a chamber to which water is accessible for the purpose of partially submerging the guard member, each guard member further having a float chamber to limit the depth of submersion thereof, the guard members being detachable from the guide members at the lower ends of the latter, whereby as a floating guard member is destroyed or loses its buoyancy it is automatically released to have its place taken by the next higher guard member. 50

2. A torpedo guard for water craft comprising guide members having means for supporting them at a distance from the hull of a craft, a plurality of buoyant guard members formed each with a water chamber 55 and with an air chamber whereby the guard member will float at a specified depth of submersion, and clips carried by each guard member and slidably engaging adjacent guide members, the clips being detachable 60 from the guide members at the lower end of the latter, each pair of guide members carrying a plurality of guard members in superposed relation, whereby the destruction of a lowermost guard member will permit 65 its detachment from its guide members and allow its place to be taken by the guard member superposed upon it.

In testimony whereof I affix my signature.
CHARLES J. MOSES.
